UNITED STATES PATENT OFFICE.

BENJAMIN GRAEMIGER, OF ZURICH, SWITZERLAND.

PROCESS OF COMPRESSING VAPOR IN MULTISTAGE CENTRIFUGAL COMPRESSORS.

1,400,813.

Specification of Letters Patent. Patented Dec. 20, 1921.

Application filed November 3, 1920. Serial No. 421,578.

To all whom it may concern:

Be it known that I, BENJAMIN GRAEMIGER, a citizen of the Republic of Switzerland, residing at Zurich, Hardturmstrasse 19, Switzerland, have invented certain new and useful Improvements in a Process for Compressing Vapor in Multistage Centrifugal Compressors; and I do hereby declare the following to be a clear, full, and exact description of the invention, such as will enable others skilled in the art to which it appertains to make and use the same, reference being had to the accompanying drawings and to letters or figures of reference marked thereon, which form a part of this specification.

This invention relates to a process for compressing vapor in multi-stage centrifugal compressors.

According to the invention a liquid of the same nature as the vapor to be compressed is introduced into the compressor behind at least one of the rotor wheels in such a form and quantity that the state of the vapor will be changed into that in which it contains not more than three per cent. by weight of liquid. The process may be carried out so that the cooling of the vapor which has been superheated through being compressed is only effected to such an extent as to obtain saturated vapor.

It is already known with air compressors of the piston type to inject water into the air to prevent too high a rise of the temperature and therefore of the power consumption. For this purpose the air from a certain stage of the compressor has been led into a special receiver into which the water has been injected whereafter the cooled air has been introduced into the next stage of the piston compressor. If the water were to be pumped immediately into the piston compressor the danger exists that the injected quantity may be too large and that water hammer occurs which might cause a bursting of the compressor. The withdrawing and re-introducing of the air from and to a special receiver causes considerable losses of energy. Moreover it is disadvantageous in most cases to get moist air by this direct injection of water. In certain cases this direct injection is inadmissible especially when the air is used for combustion because a considerable portion of the energy contained in the fuel is then used for evaporating the particles of

water contained in the air and is thus utilized inefficiently for combustion purposes.

The conditions for carrying into effect the process according to the present invention are quite different. The liquid injected into the compressed vapor being of the same nature as that of which the vapor is formed, the injected liquid *i. e.* the cooling liquid, cannot have any harmful effect but it increases the useful quantity of vapor obtained. The mixing of liquid and vapor takes place in the rotary compressor itself without the vapor being withdrawn from the compressor in a complicated way and then reintroduced into the latter. Only care has to be taken that the ratio between the injected liquid and the compressed vapor is chosen such that the vaporous mixture does not contain more than three per cent. by weight of liquid. It is a well known fact that with compressing vapors in rotary compressors the vapor leaving any rotor wheel or diffuser connected to the latter is superheated, therefore such a quantity of liquid may be injected that the vapor is cooled down from its initial highly superheated state to approximately its saturated state. If too great a quantity of liquid were injected particles of water might be admixed in a considerable quantity to the vapor worked upon by the following rotor wheel which water would corrode the blades of the rotor wheel and acceleration would have to be imparted to the water by the following rotor wheels involving a great amount of expenditure of power. The additional liquid is not only admixed in a limited quantity but also preferably in a finely distributed state. This admixing can for instance be effected in the shape of fine sprays. The mixing is enhanced by utilizing liquid jets of a great surface which can easily be divided up. Hollow-jets are very suitable for this purpose. A further method of admixing liquid to the vapor is described hereinafter when explaining the constructional examples for carrying out the process. With a given circumferential speed and a given number of stages, for instance with a six-stage centrifugal compressor, an increase in pressure of approximately 6% may be obtained by injecting liquid. On account of the comparatively low initial temperatures in front of the various rotor wheels the theoretical and also the actual power used for compressing a given weight

of vapor, measured at the discharge end, is smaller than if no cooling liquid were injected. When cooling compressed air by injecting water waste energy in the shape 5 of heat is carried away by the heated up water; in the present process, however, the energy supplied to the vapor in centrifugal compressors is not lost but is utilized in generating vapor of the same kind. This 10 increase of vapor may amount to 1.8-5% of the weight of vapor entering the suction end of the compressor. As the highest temperature occurring is considerably lower than if no liquid were injected, the mean 15 temperature of the compressor casing is lower and consequently its radiation of heat and the energy losses resulting therefrom are smaller.

All the advantages inherent to the present 20 process are of special importance in the compression of lye vapors for the purpose of utilizing such vapors as heat generating means when evaporating fresh lye. The above mentioned advantages are all the more 25 apparent the higher the ratio of compression is.

The liquid to be injected consists preferably of very pure condensed vapor formed 30 at any point along the path of the vapor. The increase of the temperature of said 35 condensed vapor increases the quantity of vapor obtained thereby and leaving the compressor as useful vapor.

In the accompanying drawings: 35 Figure 1 is a quantity-pressure diagram for different compressions of steam;

Figs. 2, 3, 4 and 5 illustrate by way of example several modifications of a device for carrying into effect the process according 40 to the invention.

In Fig. 1 the abscissas of the diagram represent evaporated quantities of steam of from 600 to 1200 kilograms per hour, the ordinates represent the corresponding pressure ratio of the final pressure p_2 to the initial pressure p_1 . The curves I, II and III represent the relation between the pressure ratio and the weight of steam with a given compressor running at a uniform 45 speed. The curves I and II show the pressure-ratios obtained in a compressor in relation to the weights of steam entering the suction end of the compressor, curve I in particular indicates the conditions prevailing 50 with compressions without the use of cooling water and curve II shows the conditions for compressions with cooling water injected. It is to be seen from the diagram that with the same quantity of steam entering the suction end of the compressor for instance 55 1000 kilograms per hour the ratio $(\frac{p_2}{p_1})$ between the final and the initial pressure is 1.6 if no cooling water is introduced 60 during the compression and 1.76 if cooling

water is introduced. The distance between the curves II and I illustrates the gain in the ratio between the pressures by the introduction of a cooling liquid. The curve III indicated in dotted lines gives a measure 70 for the gain in the quantities of vapor obtained by the injection of cooling water. The distance A-B shows the gain in the pressure ratio with a constant quantity of steam of 1000 kgs/hour at the suction end 75 of the compressor, the horizontal distance B-C=50 kilograms per hour indicates the increase of the weight of steam in the compressor while maintaining the pressure ratio which corresponds to the ordinate of the 80 point B. The point C shows the higher pressure ratio attained in the same compressor running at the same speed and the greater weight of vapor leaving the compressor as compared with the working of the 85 compressor without the introduction of cooling liquid (i. e. point A).

Fig. 2 illustrates in a vertical longitudinal section the upper part of a four-stage centrifugal compressor, through the branch 90 1 of which the steam to be compressed enters, which is compressed consecutively in the rotor wheels 2, 3, 4, 5 whereupon it leaves the compressor through the branch 6. By means of the conduit 7 and 8 pressure 95 water can be injected in a finely distributed manner through nozzles behind the first rotor wheel (2) and the third rotor wheel (4). Fig. 3 illustrates a special exemplification of an injector nozzle. Inside the casing 31 a rod 32 is provided which can serve to control and shut off the fluid passage inside the nozzle casing by means of the conical part 33; further the extended part 34 of the rod causes the water fed through 100 branch 35 to the nozzle casing to leave the latter in the shape of a hollow jet. In this manner the water offers a large surface on which the steam can act so that the water is finely atomized in a very short time and is, 110 at least for the greatest part, evaporated.

Fig. 4 illustrates the lower half of a four stage centrifugal compressor, in which a modification of the supply of the cooling water into the path of the steam is shown, 115 whereby the conduits 7 and 8 of Fig. 2 can be dispensed with. A small auxiliary pump 11 forces water through the pipe 12 into a collecting space 13 into which the highly compressed steam enters on leaving the last 120 rotor wheel 5. The water accumulates at the bottom of the collecting space 13. Part of said water is evaporated by being in contact with the highly compressed steam and contributes to lower the temperature of said 125 steam. As, however, only a small portion of the steam contacts with the comparatively small surface of the water and as it takes a certain time in order to evaporate a given quantity of water a small storage of water 130

can be easily maintained at 14 by supplying continuously fresh water through pipe 12, although the steam contained in the space 13 is either slightly superheated, saturated or containing a quantity of liquid amounting to not more than 3 per cent. by weight. In the lowest part of the casing by-pass channels 16, 17, 18 are arranged by the interposition of a covering plate 15, through which channels water from the storage 14 flows to the space 19 on account of the difference in pressure between spaces 13 and 19. At the bottom of space 19 the water collects and forms a storage 20. In a similar manner water is flowing from space 19 to space 21 and from there to space 23 through a channel 22 which may for instance be arranged horizontally. From the space 23 the water enters finally the suction space 25 through the channel 24. Out of space 25 the water is drawn through the suction pipe 26 by the pump 11 and thereupon repeats its circuit. If the quantity of water delivered by the pump 11 is too great, part of it can be returned to the suction pipe 26 through pipe 27. The quantity of cooling water evaporated in the compressor is replaced by fresh water, which enters the suction pipe 26 by means of the pipe 28. In order to prevent the water on entering the space 19 through channel 18 from squirting too high and from getting admixed to the steam in the shape of drops of water whereby the runner wheel 5 would have to deal not only with steam but also with water, a baffle plate 29 in the shape of an angle iron may for example be secured to the casing above the channel 18. Too great an evaporation and splashing of the water can also be prevented by providing a sieve above the stored water. This modification is shown by way of example in the space 23 of Fig. 4 in a vertical longitudinal section and in Fig. 5 in a vertical cross-section along line D—E of Fig. 4. The sieve 30 is fixed to the compressor casing at such an elevation that it is only a small distance above the normal water level. A sufficient exchange of heat from the steam compressed in the rotor wheel 2 to the stored water can take place through the openings of the sieve; the steam generated from said water rises through the openings of the sieve into the large space 23 where it mixes with the compressed steam, thereby preventing an excessive increase of the temperature of the latter. Furthermore the sieve prevents that the steam rotating in the space 23 in the direction of arrow IV carries away particles of water and causes a wave in the water as indicated by arrow V shown in dotted lines, whereby the water would be admixed to the steam in the shape of drops.

I claim:

1. A process for compressing vapor in multi-stage centrifugal compressors, comprising introducing into the compressor behind at least one of the runner wheels such a quantity of a liquid of the same nature as the vapor as to obtain a compressed vapor that does not contain more than three per cent. by weight of liquid. 65
2. A process for compressing vapor in multi-stage centrifugal compressors, comprising introducing into the compressor behind at least one of the runner wheels such a quantity of liquid of the same nature as the vapor to cool the vapor superheated in one runner wheel to its saturated state and to obtain a compressed vapor that contains not more than three per cent. by weight of liquid. 75
3. A process for compressing vapor in multi-stage centrifugal compressors, comprising introducing into the compressor behind at least one of the runner wheels such a quantity of liquid of the same nature as the vapor in a finely distributed state to obtain a compressed vapor that contains not more than three per cent. by weight of liquid. 85
4. A process for compressing vapor in multi-stage centrifugal compressors, comprising introducing into the compressor behind at least one of the runner wheels such a quantity of liquid of the same nature as the vapor in the shape of hollow jets to obtain a compressed vapor that contains not more than three per cent. by weight of liquid. 95

In testimony that I claim the foregoing as my invention, I have signed my name.

BENJAMIN GRAEMIGER.
